US00D933484S

(12) **United States Design Patent** (10) **Patent No.:** **US D933,484 S**
Maclam et al. (45) **Date of Patent:** **** Oct. 19, 2021**

(54) **BOTTLE**

- (71) Applicant: **The Procter & Gamble Company**, Cincinnati, OH (US)
- (72) Inventors: **Dennis Lee Maclam**, Mason, OH (US); **Tracy Renae Murchison**, Springboro, OH (US); **Luis Peraza**, New Albany, OH (US)
- (73) Assignee: **The Procter & Gamble Company**, Cincinnati, OH (US)
- (**) Term: **15 Years**
- (21) Appl. No.: **29/761,039**
- (22) Filed: **Dec. 7, 2020**

Related U.S. Application Data

- (62) Division of application No. 29/676,160, filed on Jan. 9, 2019, now Pat. No. Des. 906,822.
- (51) **LOC (13) Cl.** **09-01**
- (52) **U.S. Cl.** **USPC** **D9/542; D9/537**

Primary Examiner — Brett Miller*Assistant Examiner* — Rani J Abdallah*(74) Attorney, Agent, or Firm* — Jason Jeffrey Camp(57) **CLAIM**

The ornamental design for a bottle, as shown and described.

DESCRIPTION

FIG. 1 is a perspective view of a bottle embodying our new design;

FIG. 2 is a front view thereof;

FIG. 3 is a left side view thereof;

FIG. 4 is a back view thereof;

FIG. 5 is a right side view thereof;

FIG. 6 is a top view thereof; and,

FIG. 7 is a bottom view thereof.

The broken lines are shown for the purpose of illustrating parts of the bottle that form no part of the claimed design.
